UNITED STATES PATENT OFFICE.

WILLIAM THOMPSON, OF KALAMAZOO, AND GEORGE W. COPE, OF DETROIT, MICHIGAN,
ASSIGNORS TO KALAMAZOO STOVE CO., OF KALAMAZOO, MICHIGAN.

DESIGN FOR A HEATING-STOVE.

No. 38,990.

Specification for Design.

Patented Jan. 7, 1908.

Application filed September 23, 1907. Serial No. 394,250. Term of patent 14 years.

To all whom it may concern:

Be it known that we, WILLIAM THOMPSON, a citizen of the United States, residing in the city and county of Kalamazoo, State of Michigan, and GEORGE W. COPE, a citizen of the United States, residing in the city of Detroit, county of Wayne, State of Michigan, have invented a new, original, and ornamental Design for a Heating-Stove.

Our new, original and ornamental design for a heating stove is illustrated in the accompanying drawing, which is a perspective view thereof.

We claim:

The ornamental design for a heating stove, substantially as shown.

WILLIAM THOMPSON.
GEORGE W. COPE.
